SHRUNK SLEEVE PACKAGE

George C. Irwin, University City, and August W. Willert, Jr., Webster Groves, Mo.; Elise V. Irwin, administratrix of said George C. Irwin, deceased

Application April 17, 1950, Serial No. 156,412

11 Claims. (Cl. 299—24)

The present invention relates generally to the packaging art and more particularly to a novel tubular container and a method of packaging material in cake or block form.

In one form, the invention comprises a single cake, or a series of cakes, wrapped individually or together in sheets of cellophane or like flexible material, and having a length of wet flexible regenerated cellulose tubing disposed around the wrapped cakes, the cellulose tubing forming a tightly fitting rigid container for the cakes when it dries and shrinks, and also forming an air-tight seal therefor.

The containers in use at the present time for deodorant blocks, moth repellent cakes, and the like, are very unsatisfactory for many reasons. They are usually made entirely of metal or else they have fiber bodies with metal ends or backs. These are heavy, cumbersome, and expensive. Furthermore, they are not completely air-tight so that with many of these containers a portion of the contents sublimates before the product reaches the ultimate purchaser.

It is an object of the present invention, therefore, to provide a novel container and method of packaging which is particularly applicable for use with cakes and blocks of a material which sublimates at normal room temperature. An example of this is paradichlorobenzene which is used both as a moth repellent and as a deodorant in lavatories.

Another object is to provide a container which is applied to the goods in the form of a flexible tubular member and which stiffens upon drying to form a rigid container and provide an air-tight seal.

Another object is to provide a novel container for moth repellent material which can be suspended in a closet or the like.

Another object is to provide a novel package of moth repellent material, the contents of which sublimate in a predetermined manner.

Another object is to provide a novel package of moth repellent material in block form which has an increased exposed surface area over an ordinary block of comparable size.

Another object is to provide a novel package of deodorant blocks in which there are external lines of demarcation between individual blocks so that the container can be severed between the blocks.

Another object is to provide a novel package for deodorant blocks whereby one block can be severed from the package without disturbing the air-tight seal of the remainder of the package.

Other objects are to provide a container which is light in weight, simple in construction, and relatively inexpensive.

Further objects and advantages of the present invention will be apparent from the following description, reference being had to the accompanying drawings wherein a preferred embodiment of the present invention is shown, in which:

2

Fig. 1 is a front elevational view of a package of moth repellent material adapted to be suspended in a closet or the like, embodying the teachings of the present invention;

Fig. 2 is a side elevational view of the package taken from the right of Fig. 1;

Fig. 3 is a rear view of the package, a portion of it being cut away to show the inner construction;

Fig. 4 is an enlarged horizontal diametrical sectional view taken on the line 4—4 in Fig. 1, the cake of material being shown partially in elevation;

Fig. 5 is a vertical diametrical sectional view of a cake of material with only the flexible material wrapped around it;

Fig. 6 is a view similar to Fig. 5 showing a modified form of wrapping;

Fig. 7 is a front elevational view of a modified form of package used with a plurality of vertically stacked cakes;

Fig. 8 is a top plan view of the package shown in Fig. 7;

Fig. 9 is a bottom plan view of the package shown in Fig. 7;

Fig. 10 is a side elevational view of the package shown in Fig. 7, a portion of the container being shown in section;

Fig. 11 is a rear elevational view of the package shown in Fig. 7, a portion of the container being cut away to show the inner construction of the package;

Fig. 12 is a horizontal transverse sectional view taken on the line 12—12 in Fig. 7;

Fig. 13 is an enlarged vertical transverse sectional view taken on the line 13—13 in Fig. 7;

Fig. 14 is a plan view of one of the cakes used in the package shown in Fig. 7;

Fig. 15 is a front elevational view of another modified form of the package which is particularly applicable for the packaging of deodorant blocks;

Fig. 16 is an end view of the package shown in Fig. 15 taken from the right side, a portion of the container being cut away and shown in cross section to better illustrate the inner construction;

Fig. 17 is an enlarged fragmentary horizontal sectional view taken on the line 17—17 in Fig. 15; and

Fig. 18 is a perspective view illustrating a method of cutting a single deodorant block from the package.

Although the container and method of packaging disclosed herein is particularly applicable for use with moth repellent cakes and deodorant blocks, it is to be understood that it is not so limited and that it can also be used with bars of soap, candy, etc.—in fact practically any material which is sold in cake, block or bar form.

Referring to the drawings more particularly by reference numerals, specifically Figs. 1 through 6, 20 indicates generally a package of moth repellent material constructed in accordance with the teachings of the present invention.

The package 20 includes a cylindrical cake of material 22, such as paradichlorobenzene, which has a side surface 23, a front surface 24 and a rear surface 26.

The front surface 24 contains a groove 28 around the periphery thereof which forms an edge 30 with the side 23 of the cake.

A cylindrical recess 32 is formed in the rear surface 26 for a purpose to appear.

The cake 22 is wrapped in two sheets 34 and 36 (Fig. 5) of a thin flexible material such as cellophane or the like. The sheets 34 and 6 are originally circular in form. One is positioned against the front surface 24 and the other against the rear surface 26. The sheets 34 and 36 are then pressed around the cake 22 and their edges brought together toward the front surface 24 as shown in Fig. 5, so as to form a flange-like portion

38. This joining together of the edges provides the first

of two seals. The flange-like portion 38 is then pressed rearwardly against the side of the cake 22. If desirable, sheets 34 and 36 could each consist of two layers of material. Thus, if one layer contained a small pinhole, it would be very unlikely that the other one would also contain a pinhole in exactly the same place. This would assure an absolutely air-tight package.

Fig. 6 shows an alternate wrapping construction in which a single sheet of material 40 is wrapped around the front of the cake 22 and the edges gathered together and twisted adjacent the rear face 26 as at 41. The free edges could also be merely overlapped.

A disc 42 of cardboard or the like is positioned adjacent the rear surface 26. The disc 42 contains a reinforced eyelet 44 adjacent the upper edge thereof and a loop of string 46 extends through the eyelet 44.

If the type of wrapping shown in Fig. 6 is employed, the twisted portion 41 is forced into the recess 32 by the disc 42. If overlapping is used, the disc 42 holds it in position.

Disposed around the edge of the disc 42 and the side surface of the wrapped cake 22 is an annular member 48 which forms a container or housing for the cake 22. The member 48 is a length of regenerated cellulose tubing such as Du Pont "Celoseal," which has been maintained in an aqueous solution to keep it soft and flexible.

The tubing is slipped rearwardly over the edges of the cake 22 and disc 42 while it is wet and flexible and as it dries it stiffens and shrinks so that it presses the flange-like portion 38 of the wrapping tightly against the side surface 23 of the cake so as to form a second seal. Thus the cake 22 is doubly sealed within an air-tight wrapping so that there is no chance of the vapor escaping during transportation and storage.

The tubing is slightly longer than the thickness of the cake 22 so that the front edge of the tubing shrinks over the edge 30 of the cake 22 and the rear edge shrinks over the edge of the disc 42 (Fig. 4), whereby when the member 48 is completely dry, it forms a rigid container for the cake 22. This container is rigid enough to support the cake 22 through all phases of its sublimation, and its weight is practically negligible.

When the tubing shrinks over the edge of the disc 42 it binds the looped string 46 tightly against the disc 42 and prevents it from pulling free. If desirable, the edge of a separate tab (not shown) can be inserted between the disc 42 and the flange portion of the annular member 48 in place of string, and the tab used for suspending the package from a support.

Furthermore, the sheets 34 and 36 and the annular member 48 can all be of different colors to enhance the appearance of the package 20.

To use the contents of the package 20, the sheet 36 (or the sheet 40, depending on which type of wrapping is used) is cut out along the groove 28 adjacent the front edge of the member 48 so as to expose the front surface 24 to the atmosphere.

As the cake 22 sublimates a depression is formed in the front surface 24 which enlarges and eventually meets the recess 32 so that the portion of the cake 22 at that phase of the sublimation is in the form of an annulus adjacent the annular member 48. The fact that the portion of the cake 22 which is adjacent the member 48 remains in solid form until a large portion of it has sublimated aids in maintaining the member 48 in annular shape.

Because the paradichlorobenzene vapor is heavier than air, the upper portion of the cake 22 will sublimate before the lower portion does, so that after the cake has been reduced to an annulus, further sublimation results in the formation of a crescent shaped portion at the bottom of the member 48.

A modified form of package 50, which is shown in Figs. 7 to 14, includes a series of semi-circular shaped cakes 52 (Fig. 14) which are stacked one on top of

the other in the manner illustrated in Fig. 13 so as to provide a flat surface 53 on one side of the stack. Each cake 52 has a flat end surface 54 and an end surface which contains a ridge 56 around the periphery thereof so as to form a recess 58 adjacent the center of the cake. A circular opening 60 is contained in the center of each cake 52.

As shown in Fig. 13, the cakes 52 are positioned so that the recesses 58 are facing toward the center of the package; the ridges 56 of the end cakes bearing against the flat surface 54 of the inner cakes, and the ridges 56 of the inner two cakes being in abutted position. This provides a recess between each cake and provides a flat surface at each end of the stack. Manifestly, the double recess could also be either between the top cake and the one adjacent thereto, or between the bottom cake and the one adjacent thereto.

A sheet 62 of cellophane or the like is wrapped around the stack of cakes 52 and the ends gathered together and sealed so as to form an air-tight wrapping.

A U-shaped supporting member 64 of cardboard or like material is positioned adjacent the wrapped stack of cakes 52. The supporting member 64 has a body portion 66 which is adjacent the flat surface 53 formed by the cakes 52, a top end portion 68 which is disposed at an angle to the body portion 66 adjacent the upper end of the stack, and a similar bottom end portion 70 which is adjacent the lower end of the stack.

Each of the end portions 68 and 70 contains circular cutouts 72 which are in alignment with the openings 60 in the cakes, for a purpose to appear.

Formed integral with the top end portion 68 is an upwardly extending tab 74 which contains an opening 76 therein for suspending the package 50 from a support.

Disposed around the wrapped cakes 52 and the supporting member 64 is a tubular member 78 of regenerated cellulose. As described above, this member 78 is slipped over the cakes 52 and the body portion 66 of the supporting member 64 while it is wet and flexible, and after it dries it forms a rigid container for the cakes and also provides a second seal for the wrapping. The member 78 is slightly longer than the stacks of cakes 52 so that the ends of the member 78 shrink around the edges of the top and bottom end portions 68 and 70 respectively of the supporting member 64 (Fig. 13), so as to maintain them securely against the ends of the stack.

If desirable, a sheet of cardboard or the like, can be wrapped around the front of the stack from one edge of the body portion 66, to its other edge. This provides a smooth surface for the tubular member 78 to bear against, thereby providing a package having a better appearance.

To use the contents of the package 50, the cutouts 72 are removed from the end portions of the supporting member 64, and the cellophane wrapping over the openings 60 broken so as to expose the interior of the cakes 52 to the atmosphere.

As shown in Fig. 13, the recesses 58 provide additional exposed surface. Because these surfaces extend transversely from the opening 60 and prevent a direct flow of vapor through the stack of cakes 52 the rate of sublimation is more uniform.

Another modified form of package 80 embodying the teachings of the present invention is shown in Figs. 15 to 18. This type of package is particularly advantageous for the packaging of cylindrical shaped deodorant blocks 82.

Each block 82 has an end surface 84 which is flat and an end surface 86 which contains a bevelled edge 88 (or a groove similar to the groove 28 of the cake 22).

As shown in Fig. 17, each block 82 is wrapped in two sheets of flexible air impervious material such as cellophane, the edges of the two sheets overlapping so as to form a seal. Manifestly, the blocks 82 can also be

wrapped in the manner illustrated in either Figs. 5 or 6, and as described above.

After the blocks 82 have been wrapped, they are stacked one on top of the other with a flat end surface 85 adjacent an end surface 86 which contains a bevelled edge 88.

Discs 90 of cardboard or like material are disposed adjacent the ends of the stack of blocks 82. Disposed around the stack of blocks 82 and the end discs 90 is an elongated tubular member 92 of regenerated cellulose.

As described above, the member 92 is slipped over the blocks 82 while wet and when it dries it forms a rigid container for the blocks 82 and also provides a second seal for the wrapping. Even if the wrappings of the individual blocks 82 are not airtight, the member 92 will prevent the escape of the vapor.

The member 92 is slightly longer than the stacks of blocks 82 so that when the ends shrink they form flange-like portions around the peripheries of the discs 90 so as to maintain them securely in place against the ends of the stack.

When the member 92 shrinks around the blocks 82 it aligns them and also forms a series of spaced annular indentations 94 between adjacent blocks (Fig. 15). These indentations are used as guides when severing a block 82 from the remainder of the package as illustrated in Fig. 18. Thus, one block at a time can be removed from the package 80 without disturbing the airtight seal of the remainder of the blocks.

Also, because the container 80 is reduced in size each time a block 82 is removed, the number of blocks remaining in the package can be easily determined at a glance and additional packages ordered before the last few blocks are placed in use.

The discs 90 prevent the end portions from being broken in shipment and also provide a surface for affixing trade-marks, description of blocks, etc. Information and trade-marks can also be applied directly to the surface of the tubing 92 and thereby obviate the necessity of separate stickers or tags being affixed to its surface.

Thus the regenerated cellulose member 92 forms a container which is only a fraction of the weight and size of the containers in use at the present time, which provides a second seal for the wrapping, and from which a single block can be removed without disturbing the airtight seal of the remainder of the package.

From the above it is apparent that there has been provided several forms of the present invention which fulfill all of the objects and advantages sought therefor.

It is to be understood that the foregoing description and the accompanying drawings have been given only by way of illustration and example, and that changes and alterations in the present disclosure, which will be readily apparent to one skilled in the art, are contemplated as within the scope of the present invention, which is limited only by the claims which follow.

What is claimed is:

1. A package, comprising at least one cake of material; flexible material in sheet form totally enclosing the sides and the ends of said cake; and a tubular member disposed around said cake and a portion only of said flexible material at the ends of said cake in close engagement therewith so as to form a container for said cake, said tubular member being of a diameter greater than the diameter of said cake and made of a material which is initially wet and flexible and which stiffens and shrinks when it dries for sealing said sheet material around the cake.

2. A package, comprising a cake of material which sublimates at ordinary room temperature; flexible material in sheet form completely wrapped around said cake so as to form an enclosure therefor; a disc-like member disposed adjacent one end of the cake; a tubular member disposed about said cake in close and binding engagement therewith so as to form a container therefor,

the end of the tubular member adjacent the disc-like member being flanged over the latter so as to hold it against the cake, said tubular member being of an initial diameter greater than the diameter of said cake and made of a material which is initially wet and flexible and which stiffens, shrinks and tightens against the cake when it dries for sealing said sheet material around the cake; and means for suspending the package from a support including a suspension device having one end which is held in fixed relationship between the cake and the tubular member.

3. A package, comprising a cake of material; sheets of flexible material disposed completely around the ends of the cake, the edges of the sheets being joined together so as to provide an enclosure for the cake and form a flange-like portion around the cake, the flange-like portion being disposed against the side of the cake; and a tubular member disposed around the cake and over the flange-like portion in close and binding engagement therewith so as to form a container for the cake and seal the edges of the sheets of flexible material against the cake, said tubular member being of an initial diameter greater than the diameter of said cake and made of a material which is initially wet and flexible and which stiffens, shrinks and tightens against the cake when it dries for sealing said sheet material around the cake.

4. A package, comprising a plurality of cakes disposed one on top of the other to form a column; flexible material in sheet form wrapped around the column so as to form an enclosure therefor; a supporting member having a body portion disposed adjacent one side of the column, the ends of the supporting member extending at an angle to the body portion adjacent the ends of the column; and a tubular member disposed around the column and the body portion of the supporting member in close proximity thereto, the ends of the tubular member being flanged over at least a portion of the ends of the supporting member to hold them against the ends of the column, said tubular member being of an initial diameter greater than the diameter of said cakes and made of a material which is initially wet and flexible and which stiffens, shrinks and tightens against the cakes when it dries for sealing said sheet material around the cakes.

5. A package, comprising a plurality of cakes disposed one on top of the other to form a column; flexible material in sheet form wrapped around the column so as to form an enclosure therefor; a supporting member having a body portion disposed adjacent one side of the column, the ends of the supporting member extending at an angle to the body portion adjacent the ends of the column; and a tubular member disposed around the column and the body portion of the supporting member in close proximity thereto, the ends of the tubular member being flanged over at least a portion of the ends of the supporting member to hold them against the ends of the column, said tubular member being of an initial diameter greater than the diameter of said cakes and made of a material which is initially wet and flexible and which stiffens, shrinks and tightens against the cakes when it dries for sealing said sheet material around the cakes.

6. A package, comprising a plurality of cakes disposed one on top of the other to form a column; a passageway extending longitudinally through said column; a supporting member having a body portion disposed adjacent one side of the column, the ends of the supporting member extending at an angle to the body portion adjacent the ends of the column and containing weakened portions in alignment with the ends of said passageway; flexible material in sheet form totally enclosing the sides and the exposed ends of said cakes in the column; and a tubular member disposed around the column and the body portion of the supporting member in close proximity thereto, the ends of the tubular member being flanged over at least a portion of the ends of the supporting member to hold them against the ends of the

column, said tubular member being of an initial diameter greater than the diameter of said cakes and made of a material which is initially wet and flexible and which stiffens, shrinks and tightens against the cakes when it dries for sealing said sheet material around the cakes.

7. A package, comprising a plurality of cakes disposed one on top of the other to form a column, at least some of the cakes having a ridge-like portion extending around at least one end thereof adjacent the periphery so as to provide chambers between adjacent cakes; a passageway extending longitudinally through said column interconnecting the chambers; a supporting member having a body portion disposed adjacent one side of the column, the ends of the supporting member extending at an angle to the body portion adjacent the ends of the column and containing weakened portions in alignment with the ends of said passageway; flexible material in sheet form totally enclosing the sides and the exposed ends of said cakes in the column; and a tubular member disposed around the column and the body portion of the supporting member in close proximity thereto, the ends of the tubular member being flanged over at least a portion of the ends of the supporting member to hold them against the ends of the column, said tubular member being of an initial diameter greater than the diameter of said cakes and made of a material which is initially wet and flexible and which stiffens, shrinks and tightens against the cakes when it dries for sealing said sheet material around the cakes.

8. A package, comprising a plurality of cakes disposed one on top of the other to form a column, each of said cakes having flexible material in sheet form wrapped around it so as to form an enclosure therefor; annular grooves around the column between adjacent cakes; and a tubular member disposed around said cakes in close engagement therewith so as to form a container therefor having indentations between adjacent cakes, said tubular member being of an initial diameter greater than the diameter of said cakes and made of a material which is initially wet and flexible and which stiffens, shrinks and tightens against the cakes when it dries for sealing said sheet material around the cakes.

9. A package, comprising a plurality of cakes disposed one on top of the other to form a column, each of said cakes having a beveled end portion so as to provide annular peripheral grooves between adjacent cakes; flexible material in sheet form totally enclosing the sides and the exposed ends of said cakes in the column; and a tubular member disposed around said cakes in close engagement therewith so as to form a container therefor having indentations between adjacent cakes, said tubular member being of an initial diameter greater than the diameter of said cakes and made of a material which is initially wet and flexible and which stiffens, shrinks and tightens against the cakes when it dries for sealing said sheet material around the cakes.

10. A package, comprising a plurality of cakes disposed one on top of the other to form a column; flat disc-like members disposed adjacent the ends of the column; flexible material in sheet form totally enclosing the sides and the exposed ends of said cakes in the column; and an elongated tubular member disposed about the cakes in close engagement therewith so as to provide a container therefor, the ends of the tubular member being flanged around the edges of the disc-like members so as to hold them securely against the ends of the column, said tubular member being of an initial diameter greater than the diameter of said cakes and made of a material which is initially wet and flexible and which stiffens, shrinks and tightens against the cakes when it dries for sealing said sheet material around the cakes.

11. A package comprising a cake of material; at least two sheets of material disposed over the ends of said cake to completely cover the same, said sheets being secured together at the side of said cake to form a flange-like portion therearound; a disc-like member disposed over one end of said cake exteriorly of the sheet material; a tubular member disposed about said cake in close engagement therewith and having flanged-over end portions bearing against the outer periphery of the ends of said cake in sealing relationship with the sheet material and said disc-like member, said tubular member being of an initial diameter greater than the diameter of said cake and made of a material which is initially wet and flexible and which stiffens, shrinks and tightens against the cake when it dries for sealing said sheet material around the cake; and means for suspending the package from a support including a suspension device having one end which is held in fixed relationship between the cake and the tubular member.
